MACHINE FOR SURFACING SHEETS

Application filed April 26, 1926. Serial No. 104,571.

This invention relates to the art of surfacing sheets for the purpose of cleaning or polishing the same, and while primarily applicable to the grinding and polishing of sheets, it is also adaptable to the brushing or buffing of sheets.

The invention has for its principal object to provide a machine for the treatment of the surface of sheets, plates or the like where-
10 in substantially the entire area of the sheet is evenly subjected to the surface treatment. It is also proposed, according to the present invention to provide a machine wherein the surface treatment of the sheets or plates may
15 be quickly and rapidly effected and without liability of injuring the sheets through burning or buckling the metal and wherein the plates may be ground or polished while held with a substantially uniform pressure against the grinding or polishing means, the grinding and polishing means being more or less flexible to yield to slight irregularities in the surface of the metal.

The invention may be readily understood
25 by reference to the accompanying drawings which illustrate a preferred embodiment of the invention, but it will be understood that I do not limit myself to the specific construction therein shown as various changes
30 and modifications may be made in the construction of the machine within the spirit and contemplation of my invention.

In the drawings:

Figure 1 is a top plan view of the entire machine showing the abrading belt supporting pulleys in dotted lines and omitting the belt.

Figure 2 is a side elevation thereof showing the abrading belt and its pulley in dotted lines;

Figure 3 is an enlarged detail view showing one end of the machine including the rack drive for reciprocating the sheet or plate supporting carriage, part of the structure being
45 broken away to show in detail the adjusting means for raising and lowering the frame of the machine;

Figure 4 is an enlarged detail view of the forward end of the plate supporting carriage;

Figure 5 is a side elevation showing a portion of the carriage apart from the rest of the machine together with the electric limit switch by means of which the movement of the carriage is controlled;

Figure 6 is an end view of that part of the machine shown in Figure 5.

Figure 7 is a diagrammatic side elevation of a slightly modified form of a machine.

In the drawings, 2 designates the bed of the machine which is supported on standards 3 and 4 at opposite ends of the bed. Secured to the underside of the bed 2 are wedges 5 which engage supporting blocks 6 in the respective standards 3 and 4. These supporting blocks can be raised or lowered by means of screws 7 in the standards.

In the center of the bed on the underside thereof is a shaft 8 having a threaded end portion 9 which passes through a nut 10 in the center of the standard 3. The other end of the shaft 8 is carried in a bearing 11 secured to the underside of the bed of the machine and has a pinion 12 thereon. This pinion meshes with a second pinion 13 on a transversely extending shaft 14. The outer end of shaft 14 projects slightly beyond one side of the bed so that an operating crank may be applied thereto. Upon rotation of the shaft 14 in the proper direction, shaft 8 will be rotated to effect an endwise travel of the bed of the machine with respect to standards 3 and 4. This endwise movement of the bed will cause the wedges 5 to move upwardly on the supporting blocks 6 to thereby effect a corresponding raising or lowering of the bed. The bed can be adjusted to be level or to have any desired degree of angularity by adjustment of the bolts 7.

Carried on the bed of the machine is a pair of rails 15 which extend along the bed more than one-half of the length thereof. At the opposite end of the bed is a second pair of rails 16 which are spaced apart slightly further than the rails 15 and which have inner ends overlapping the ends of the rails 15. The inner ends of the rails 16 are inclined as shown at 17.

Supported above the bed for movement therealong on wheels 18 and 19 is a carriage

20. The wheels 18 are reversed with respect to wheels 19, and the wheels 18 are adapted for travel on the rails 16, while the wheels 19 are adapted for travel on the rails 15. The carriage 20 is preferably formed of cast iron and has a relatively thick compressed asbestos mat or board 21 covering the greater portion of its area. This mat is leveled off and smoothed on its top surface, and may if desired provide the support for the sheets to be treated, although there is preferably a thin layer of sheet metal 22 on top of the pad 21. As best shown in Figure 4 the mat 21 does not extend entirely to the forward end of the carriage, but terminates a short distance back of the forward or inner end of the carriage. Mounted in this forward portion of the carriage is a transversely extending eccentric 23 on a shaft 24. Over the eccentric and spaced a slight distance thereabove is a plate 25, which is preferably one leg of an angle iron arranged transversely across the end of the machine, this angle iron having a depending leg 26 which is bolted at 27 to the end of the carriage. The eccentric 23 together with the overhanging lip or plate 25 provides the sheet clamping means on the carriage. As shown in Figure 4 the end of a sheet or plate, designated A, is projected under the overhanging lip after which the shaft 24 is operated to clamp the end of the plate against the said overhanging lip.

Secured to the underside of the carriage is a longitudinally extending rack 28 having a forward end portion 29 which is inclined with respect to the portion 28 to the same extent and degree that the ends of the tracks or rails 16 are inclined at 17. This is for a purpose to be hereinafter more fully described.

At approximately the center of the bed of the machine is another standard or supporting frame 30 having adjustable bearings 31 of a standard or preferred type in the top thereof, these bearings being adjustable longitudinally of the bed of the machine by means of hand wheels 32. The bearings 31 carry a shaft 33 on which is a sheet surfacing element 34. This is preferably in the form of a buffering wheel having a width greater than the width of the carriage. Instead of being a buffering wheel, however, it may be any suitable cylindrical body which is preferably flexible to a slight extent, or it may be a brush. When the machine is used for merely cleaning plates the body 34 may be a brush. When it is used for polishing plates it may be an ordinary buffering wheel. For grinding and polishing it is preferably, however, a buffering wheel around which is passed a flexible belt 35 which may have abrasive material carried on its outer surface. For coarse grinding the belt 35 would have an abrasive of suitable grain applied thereto, whereas for polishing the belt would have a felt surface with a suitable polishing compound on the felt. The

outer end of the belt passes around rigid driving pulley 36 carried in adjustable bearings 37 on a stand 38 at the rear end of the machine. A pulley 39 may be provided for driving the pulley 36 to operate the belt 35.

The element 34 around which the belt 35 passes is located over the inner end of the carriage and at a suitable elevation above the bed of the machine.

Carried in the bed of the machine on a shaft 40 is a pinion 41 which meshes with the rack 28-29. This pinion may be driven in any suitable way. I have illustrated the drive for the pinion as including a chain 42 meshing with a sprocket 43 on the shaft 40 and with a second sprocket 44 on a shaft 45. Shaft 45 is driven through a suitable driving element such as pulley 46 from a reversible motor not shown.

In the operation of the machine the wheels 18 are normally at the bottom of the incline tracks 17 and the carriage is at its rearmost position. The wheels 19 always remain on the rails 15. In this normal position it will be seen that the carriage is inclined downwardly to a slight extent. It is for this reason that the forward end 29 of the rack 28 is inclined, that is, so that it may remain in engagement with the driving pinion 41 in the bed of the machine. Upon rotation of the pinion 41 in a counter clockwise direction as viewed from Figure 3, the carriage will be caused to travel forwardly. As it travels forwardly the wheels 18 will roll up the inclined ends 17 of the rails 16. By the time that the clamping mechanism at the forward end of the carriage has been advanced forwardly beyond the lowest part of the belt or element 34 the carriage will move horizontally along the rails 16 without further vertical movement. This initial upward and forward movement of the carriage is for the purpose of permitting the clamp to clear the sheet treating element and raise the carriage sufficiently to bring the sheet A into contact with the sheet treating element. When the carriage has traveled the desired distance in one direction it is reversed and it travels in the opposite direction. When it approaches its rearmost position the wheels 18 ride down the incline through 17 so that the sheet clamping means will clear the sheet treating element.

For effecting automatic reciprocation of the carriage I preferably provide a pair of adjustable fingers 47 and 48, respectively, at one side of the carriage. For this purpose one side of the carriage has a flanged edge portion 49, as best shown in Figure 6, and the respective fingers 47 and 48 are slotted to engage the flanged portion 49. Each of the fingers is provided with a clamp nut by means of which it can be set in a given position. Ordinarily the forward finger 47 remains permanently set in one position while

the finger 48 is adjusted according to the length of the sheet or plate to be treated. These fingers have oppositely offset terminal portions which cooperate with the arms 47^a and 48^a respectively of the motor reversing switch 50. This switch may be of any well known type commonly referred to as a limit switch. This switch will control the motor which drives the pulley 46 in a manner well understood to those skilled in the art. As thus arranged, the carriage will travel from the normal retracted position forwardly until the finger 48 contacts with switch contact 48^a to reverse the driving motor and thereby reverse the direction of travel of the carriage. The carriage will then travel back to the starting position after which it will again start forward, unless it is otherwise stopped.

In the usual practice of grinding or polishing a plate, the plate will pass back and forth under the surface treating element two or three times. The sheet or plate needs to be held at the forward end only with the belt 35 traveling in the direction of the arrow in Figure 2. The surface of the belt or the other sheet treating means, whatever it may be, will not contact with that portion of the plate which is engaged in the sheet holding means, but will be held in contact with the remaining portion of the sheet. To clean or otherwise treat the end of which is engaged under the clamping means, it is necessary to reverse the sheet on the carriage.

By a proper adjustment of the height of the bed through the mechanism hereinbefore described the surface of the carriage may be raised or lowered with respect to the grinding or polishing belt 35 so as to secure a proper pressure of the belt against the plate. This adjustment of the bed also serves to permit the machine to be used on plates of different thicknesses. By adjustment of the screws 7 it is possible to keep the surface of the carriage level during the portion of its travel under the polishing belt, or to adjust the surface of the carriage to accommodate the machine to the treating of plates of uneven thickness.

By passing the abrasive belt 35 around a yieldable or flexible member 34, such for instance as a wide buff wheel, the plate or sheet to be polished can be pressed against the belt with considerable pressure so as to secure a sufficient grinding or polishing action. When the sheet is pressed against the belt in this manner the buff will compress and let the belt flatten to a certain extent so as to increase its area of contact with the plate and thereby secure a more efficient abrasive or polishing contact. This feature of the invention is particularly claimed in my co-pending application, Serial No. 104,570, filed April 26, 1926.

The machine may be adapted to the treating of plates or sheets whose width is greater

than the width of the carriage. This may be done by adjusting the bearings 31 for the member 34 so that it will be at an angle other than a right angle to the path of travel of the carriage. This adjustment of the member 34 will cause the belt to shift to one side or the other of the member 34, according to the direction in which the member 34 is set, so that the belt will polish one side of a wide plate overhanging the carriage. Then by reversing the direction in which the member 34 is set, the belt could be caused to travel to the other edge of the member 34 to polish the overhanging edge of the sheet at the other side of the carriage.

In the arrangement shown in Figure 7 the carriage travels along the track without vertical movement but has means thereon cooperating with means on the surface treating element for effecting a vertical movement of the latter when the clamp on the carriage moves under it. In this arrangement, 51 designates the bed of the machine having a carriage 52 movable therealong and on the carriage is a clamping means 53 similar to that hereinbefore described. Supported over the path of travel of the machine is a surface treating element 54 preferably in the form of a continuous belt passing around a cylindrical body 55. The cylindrical body 55 is carried in vertically slidable bearings 56 on side posts 57. Depending from the bearing blocks 56 is an extension 58 preferably having a cam roller 59 thereon. Secured to the side of the carriage is an inclined cam surface 60 properly positioned to engage the roller 59 and raise the bearings for the cylindrical body when the clamping means on the carriage is moving under the lowest portion of the belt. This arrangement constitutes only a reversal of the embodiment shown in Figures 1 and 2 wherein the surface treating element moves with respect to the carriage instead of the carriage moving vertically with respect to the surface treating element.

An advantage of the present invention arises from the fact that the sheets to be treated are automatically reciprocated under the sheet treating element and that the clamping means for the sheets or plates are so disposed that they are not brought into contact with the sheet treating means. Further advantages arise from the provision of means for raising and lowering the bed of the machine and adjusting it as desired. The machine is rendered substantially automatic by the provision of the automatic reversing switch. Further advantages arise out of the fact that with the machine as thus arranged the plates can be evenly and uniformly treated with rapidity and economy. The asbestos pad on which the sheets are supported serves to prevent the heat produced in the operation from the carriage, thereby preventing the warping thereof due to unequal heating.

This pad gives to the sheet being treated a limited resiliency with respect to the sheet treating means, and as stated above, a thin layer of sheet metal as shown at 22 is preferably placed on top of the pad 21 for absorbing heat from the sheet being treated. In this way the sheet being treated is provided with means for absorbing the excess heat and such heat is prevented from injuring the metal top of the carriage. In many instances heretofore it has been experienced that the carriage top has warped due to the heat from the sheet being treated. Another very desirable advantage of this pad lies in the fact that it greatly decreases the noise of the machine. While I have shown and described the clamping element as being disposed at the extreme forward end of the carriage, it may be otherwise located or disposed at the opposite end, the incline in the rails, or the incline on the carriage, being correspondingly positioned.

I claim:

1. A machine for treating the surface of plates and the like including a carriage, a clamping means on the carriage at one end only, a surface treating element in the path of travel of the carriage clamping means, means for reciprocating the carriage, a guideway along which the carriage travels, one end of said guideway having an incline therein whereby the clamping means at one end of the carriage may move under the surface treating element without contacting therewith and whereby the carriage and clamping means will be raised upon further movement thereof in one direction to bring a plate on the carriage into contact with the surface treating element.

2. In a machine of the class described, a bed, rails on the bed, a carriage having a clamping means at one end movable along the rails, said rails having an incline therein, a surface treating element over the bed adjacent the incline portion of the rails, and means for reciprocating the carriage along the rails, said incline in the rails serving to impart a vertical movement to one end of the carriage to lower the clamping means beneath the surface treating element when the carriage travels along the incline portion of the rails.

3. In a machine of the class described, a bed, rails on the bed, a carriage movable along the rails and having a work-clamp at one end, said rails having an incline therein, a surface treating element over the bed adjacent the incline portion of the rails and in the path of said work-clamp, and means for reciprocating the carriage along the rails, said incline in the rails serving to impart a vertical movement to one end of the carriage and its clamp when the carriage travels along the incline portion of the rails, means for longi-

tudinally adjusting the bed, and means for vertically adjusting the bed.

4. In a machine of the class described, a plate treating element, a carriage movable beneath the plate treating element, a guideway along which the carriage moves, a plate clamp at the forward end of the carriage normally lying in the plane of said plate treating element, said guideway having a depression therein adjacent the plate treating element, the carriage having wheels thereon which ride in the guideway, said depression permitting the forward end of the carriage and its clamp to lower when it is under the surface treating means whereby the surface treating means will not be brought into engagement with the plate clamping means.

5. A machine for surfacing sheets comprising a bed having a guideway thereon, the said guideway comprising a pair of spaced rails disposed on each end of the bed, the adjacent ends of the said rails connected together and provided with an incline thereon, the space between the rails on one end being greater than the space between the rails on the other end, a reciprocated carriage carried by the said rails having wheels for engaging and cooperating with the said rails, the wheels on one of the said carriages being reversed from the wheels disposed on the other end, an abrading element disposed above the said carriage and means for permitting one end of the carriage to pass under the abrading element free from contact therewith, the said means causing the remaining top portion of the carriage to contact with the abrading element.

In testimony whereof I have hereunto set my hand.
